UNITED STATES PATENT OFFICE.

OLE J. OLSON, OF NASHUA, MONTANA, ASSIGNOR OF ONE-HALF TO PETER R. ROST, OF GLASGOW, MONTANA.

TRACK-CLEANING DEVICE.

1,416,231.

Specification of Letters Patent. Patented May 16, 1922.

Application filed March 2, 1921. Serial No. 448,990.

To all whom it may concern:

Be it known that I, OLE J. OLSON, a citizen of the United States, residing at Nashua, in the county of Valley and State of Montana, have invented certain new and useful Improvements in Track-Cleaning Devices, of which the following is a specification, reference being had to the accompanying drawings.

10 This invention relates to improvements in track cleaning devices and more particularly to a device adapted for removing excess ballast and cinders from between the rails of the track.

15 An important object of the invention is to provide a device of this character which removes the cinders, ballast or the like from between the tracks and deposits the same at the side of the track or into a vehicle beside 20 the track.

25 A further object of the invention is to provide a device of this character which is extremely simple in construction and easy to operate, and the parts of which are so constructed that they have a maximum length of life.

Other objects and advantages of the invention will become apparent throughout the course of the following description.

30 In the accompanying drawings, wherein for the purpose of illustration is shown a preferred embodiment of my invention and wherein like reference characters designate like parts throughout,

35 Figure 1 is a plan view of my track cleaner;

Figure 2 is a side elevation thereof;

Figure 3 is a longitudinal view taken therethrough, and

40 Figure 4 is a section taken on the line 4—4 of Figure 2.

Referring now more particularly to the drawings, the numeral 10 indicates flanged car wheels adapted to travel upon the rails

45 11 of the track and arranged in pairs to support a frame 12.

The frame 12 has extending upwardly therefrom adjacent the rear end thereof, spaced supports 14 having pivotally mounted therebetween side frames 15 inclining downwardly toward the rear end of the frame and having their lower ends arranged in proximity to the right-of-way between the tracks. In the side frames 15 adjacent the 55 ends thereof are mounted upper and lower

shafts 16 and 17, approximately alined with the ends of a flooring 18 extending between the side frames. The shafts 16 and 17 have mounted thereon drums 19 upon which are mounted spaced belts 20 having secured thereto flights 20^a which in the travel of the belts upon their upper run engage the upper surface of the flooring 18 with a scraping action.

To one of the side frames 15 an adjustment lever 21 is secured providing means whereby the angular positioning of the side frames and conveyor may be attained. The rear end of the lever 21 coacts with a vertical standard 22 having formed therein notches 23 adapted to secure the lever in the inoperative or operative positions as may be desired. Pivottally secured to the lower ends of the side members 15 are the angular side portions 24 of a scraper member 25, the lower end of which when the conveyor is in the operative position extends downwardly so that it passes immediately above the line of the upper surface of the ties of the track. Mounted in the angular side portions 24 of the scraper member 25 adjacent the lower end thereof is a transversely extending shaft 26 forming the pivotal connection between the side members 15 and the scraper and having secured thereto radially extending blades 27. To the upper end of the supports 14 a transversely extending member 14^a is secured having extending upwardly therefrom approximately centrally thereof, a stem or guide member 28 which is directed through an opening formed in the upper end of the scraper member 25. A coil spring 29 surrounds the guide member 28 intermediate the transverse member 14^a and the guide member, normally forcing the upper end of the guide member upwardly for engagement with a pin 30.

Each of the rear wheels 10 of the device has secured thereto or formed thereon, one of a pair of complementary clutch sections, 100 as at 31, and the axles of these wheels are extended beyond the outer surfaces thereof as indicated at 32. These axles form a mounting for sprocket wheels 33, the sprocket wheel at one side being connected to a 105 sprocket wheel 26^a secured to the shaft 26 by a sprocket chain 26^b and at the other side being connected to a sprocket wheel 16^a secured to the shaft 16 by means of a sprocket chain 16^b. The sprocket members 33 are 110

shiftable upon the shafts 32 and are each provided with the second section of the complementary clutch sections above mentioned, as at 33^a. The hubs of the sprocket members 33 are grooved, as at 34, for the reception of shift forks 35 formed upon the ends of levers 36. These levers are pivotally mounted intermediate their ends upon the frame, as at 37, and have their rear ends 10 coacting with adjusting members 36^a, each provided with stops 36^b for holding the levers in operative or inoperative positions so that the clutch sections may be held in engaged or disengaged positions as desired.

15 Pivottally mounted upon the frame beneath the upper end of the conveyor, to receive material discharged therefrom, is a pan 39, the bearings 40 of the pan being disposed adjacent one side of the frame and 20 the adjacent end of the pan projecting upon the side of the frame so that it extends beyond the sides of the track, as at 41. Adjacent the opposite end of the pan a standard 42 is secured to the frame and has pivotally 25 mounted thereon a lever 43, one end of which pivotally engages the adjacent end of the pan, as at 44. The ends of the operating levers 21, 36 and 43 are all disposed adjacent an operator seat, as indicated at 30 45, for facility in handling.

In the use of my device the same is attached to a source of power by means of a drawbar 13 or some similar expedient, or the device may be provided with power by 35 which it may be self-propelled, if desired. Upon reaching the seat of operations, the operator engages the lever 21 with his hand elevating the same to engage with the upper notch, and the scraper 25 is brought into engagement with the cinders or similar material 40 intermediate the tracks. The levers 36 are now shifted to engage the clutches causing the shaft 26 with its radial arms to rotate, and the conveyor belt to shift in the directions suggested by the arrows in Figures 45 2 and 3. By this action the radial arms throw the cinders collected by the scraper 25 upon the platform of the conveyor where they are carried upwardly by the flights 28 50 and deposited in the pan 39. When a sufficient quantity has been collected the pan 39 may be tilted to dump the same at one side of the right-of-way from which point it may be collected with a cart or the like.

55 Particular attention is directed to the fact that in event of the scraper 25 coming into engagement with any solid substance such as the upwardly projecting portion of a

crooked tie, the spring 29 will give, permitting the scraper to pass thereover without 60 injury.

From the foregoing it is believed to be obvious that I have constructed a rail cleaning device which is particularly well adapted for the use for which it is intended by 65 reason of the facility with which it may be operated and by reason of the cheapness with which it may be manufactured. It will furthermore be obvious that the structure of the same as hereinabove set forth is 70 capable of some change and modification without materially departing from the spirit of my invention, and I accordingly do not limit myself to such specific structure except as hereinafter claimed. 75

What I claim is:

1. In a track cleaning device, a wheel supported frame, an inclined conveyor frame, side members pivotally connected therewith intermediate their ends, shafts rotatably engaging the ends of said side members, a conveyor mounted thereon, a scraper embodying angular side portions pivotally engaging the side members of the frames adjacent the lower ends thereof, a blade carrying shaft rotatably engaging the side portions of the members, means for adjusting the angular position of the conveyor, a connection between a wheel of the frame and one of the conveyor shafts, a connection between a wheel of the frame and the blade carrying shaft, and a yieldable connection between the frame and the upper end of the scraper forcing the lower end of the scraper downwardly. 90 95

2. In a track cleaning device, a wheel supported frame, supports extending upwardly therefrom, inclined conveyor side members pivotally mounted upon said supports intermediate their ends, shafts rotatably engaging the ends of said side members, a conveyor mounted on the shafts, a scraper embodying angular side portions, a shaft rotatably mounted in the side portions of the scraper and in the lower ends of the conveyor side members, a yieldable connection between the upper end of the scraper and the frame normally forcing the lower end of the scraper downwardly, a driving connection between one of the wheels of the frame and the conveyor, and a driving connection between one of the wheels of the frame and the last named shaft. 100 105 110

In testimony whereof I hereunto affix my signature.

OLE J. OLSON.
